(57) CLAIM

The ornamental design for a shampoo dispenser for animals, as shown and described.

DESCRIPTION

FIG. 1 is a front, top and side-perspective view of a shampoo dispenser for animals embodying my new design;

FIG. 2 is a front elevational view thereof;

FIG. 3 is a rear elevational view thereof;

FIG. 4 is a left-side elevational view thereof;

FIG. 5 is a right-side elevational view thereof; and,

FIG. 6 is a top plan view thereof, the bottom plan view being a mirror image.

The elements rendered in broken line are for illustrative purposes only and form no part of the claimed design.
